INSECTICIDE FORMULATION

Chester C. Crawford and Lloyd L. Jaquier, Jr.,
Bartlesville, Okla., assignors to Phillips Petroleum Company, a corporation of Delaware

Application December 4, 1946, Serial No. 713,902

12 Claims. (Cl. 167—22)

1

This invention relates to improvements in insecticidal compositions containing mixtures of branched chain paraffin hydrocarbons. In one particular aspect it relates to solvents for toxic materials used as insecticides which show synergistic insecticidal power with commonly used toxic materials.

It has long been known that petroleum fractions boiling in the kerosene range are excellent solvents for toxic materials used as insecticides. Examples of such toxic materials are pyrethrins, DDT, rotenone, etc. Typical fly sprays have been made from a highly refined kerosene fraction, a toxic material such as pyrethrum extract and a perfume. DDT and rotenone have also been used extensively in solution in kerosene with or without an added perfume.

It has recently been shown that substantially pure isoparaffinic base oils of similar boiling range are excellent base oils for insecticides containing such toxic materials and have the properties of being non-toxic to animals and plants and of causing relatively little swelling of natural or synthetic rubbers brought in contact therewith. These isoparaffinic base oils are ordinarily prepared by the alkylation of an olefin with an isoparaffin using HF, AlCl₃, H₂SO₄ or other suitable catalyst, or by processes involving polymerization of olefins followed by hydrogenation according to well known methods for producing high octane motor fuels. When compounds boiling in the motor fuel range are distilled from the products of such reaction a residue of higher boiling branched chain paraffins is obtained. This residue usually contains materials boiling from about 350° F. to 600° F. with a small amount of higher boiling materials. This residue is composed essentially of branched chain paraffin hydrocarbons with only very small amounts of straight chain paraffins and contains substantially no cycloparaffins or unsaturates. Obviously such materials may be fractionated to obtain cuts of any boiling range desired and such cuts may be further treated to remove impurities, if present.

It has been believed, in the prior art, that such

2

isoparaffinic cuts have insecticidal properties approximately equivalent to those of kerosene, as is shown by the tables in columns 3 and 4 of U. S. Patent 2,405,775 issued to Bradley August 13, 1946.

5 It is an object of this invention to provide insecticidal compositions wherein the combination of a toxic material and a selected fraction of branched chain hydrocarbons results in a synergistic increase in insecticidal power.

10 Another object is to provide a branched chain paraffin solvent for insecticidal materials which has optimum boiling range.

Another object is to provide a branched chain paraffin solvent which shows substantial synergistic increase in insecticidal power when employed with many commonly used toxic materials.

15 Other objects and advantages will become apparent to those skilled in the art as this disclosure proceeds.

20 We have discovered that certain definite fractions of branched chain paraffin hydrocarbons, substantially free from impurities when used as solvent for common toxic materials such as pyrethrins, rotenone, 2,2-bis (parachlorophenyl) - 25 1,1,1-trichloroethane usually known as "DDT," 2,2 - bis (parachlorophenyl - 1,1 - dichloroethane also known as "DDD," benzene hexachloride and butyl carbitol thiocyanate commercially called "Lethane" result in solutions having greatly increased insecticidal power, as compared to acid washed kerosene fractions or other alkylate fractions containing the same proportions of the same toxic materials. We have found the increase in insecticidal power to be synergistic and not additive, as the most effective fractions of branched chain paraffins are less toxic to insects than ordinary kerosene when used without added toxic materials.

30 The branched chain paraffin fractions which we prefer to use are prepared from heavy alkylate or other stock consisting essentially of branched chain paraffin hydrocarbons by methods shown in the copending applications of Legatski and Crawford, Serial No. 616,930, filed September 17, 1945, 35 now Patent 2,468,986, issued May 3, 1949, and

Crawford and Morris, Serial No. 617,870, filed September 21, 1945, now Patent 2,463,601, issued March 8, 1949. Such fractions are composed almost entirely of branched chain paraffin hydrocarbons, may have any boiling range desired, and are substantially free from products of hydrocarbon oxidation. However we do not wish to limit our invention to branched chain paraffin hydrocarbons prepared by the above methods. Any method may be used which results in a fraction of branched chain paraffin hydrocarbons of desired boiling range and substantially free from other materials.

The accompanying drawing shows a smooth curve representing the relative insecticidal power of solutions containing 0.1 per cent pyrethrins in various branched chain paraffin fractions. The boiling ranges of the individual fractions compared are shown by the short horizontal lines. The 24 hour kill of the official Peet-Grady test for evaluating fly sprays is plotted against boiling range of the solvent. An optimum boiling range for branched chain paraffin solvents is shown to be from about 360° F. to 420° F. and a second wider range from 300° F. to 420° F. would give far greater killing power than any range lying outside these limits.

We prefer to use a fraction of branched chain paraffin hydrocarbons boiling in the range from 360° F. to 410° F., as such narrow boiling range provides a very uniform evaporation rate and eliminates any residual oil film or stain. Typical characteristics of such solvent are:

Properties	Test Results	Test Method
Distillation (760 mm.)		
IBP° F.	368	ASTM D86-45.
10%	372	
20%	373	
50%	375

Residual Odor Test.	None	
Odor.	¹ Neutral	

¹ H. A. Gardner, "Physical and Chemical Examination of Paint, Varnish Lacquers and Colors," 6 ed., 1933.

² No naphtha or kerosene odor.

A boiling range from 360° F. to 410° F. in connection with a flash point of not less than 140° F. is probably the most outstanding physical characteristic of our preferred solvent.

We have found that considerable variation from the above characteristics may be present and the solvent will still have marked synergistic effect with commonly used toxic materials. For instance the boiling range may be widened to 300° F. to 480° F. with corresponding changes in other characteristics while lowering the synergistic effect of the solvent to only a relatively small degree.

For purposes of illustration only and not with intent to limit our invention thereto, data obtained with a solvent having the characteristics set forth above are shown in the following examples.

4 Example I

For the purpose of choosing the best deodorized kerosene insecticide base oil obtainable on the market for comparison with our preferred solvent, four widely used insecticide base oils were used as solvents for the preparation of solutions containing 0.1 per cent pyrethrins. These solutions were compared with a solution of 0.1 per cent pyrethrins in our preferred solvent. The standard Peet-Grady test for evaluating fly sprays was used. The following results were obtained:

	Per Cent Kill, 24 Hours	10 Min. Knock-down	O. T. I. Difference
Base Oil A	40.8	99.1	+2.6
Base Oil B	39.6	99.2	+1.4
Base Oil C	43.7	99.1	+5.5
Base Oil D	47.0	98.9	-1.7
Our Preferred Solvent	82.5	99.1	+33.8

Base Oil C was selected as the best of the commercially available insecticide base oils for further comparison with our preferred solvent in the preparation of insecticides.

Example II

Solutions of pyrethrins in base oil C of Example I were compared with solutions of pyrethrins in our preferred solvent having the same pyrethrin content. A modified Peet-Grady Free Flying test was used. The modification consisted of the use of a chamber about three times standard size. In all comparative determinations 30 ml. of insecticide were sprayed into a 650 cubic foot chamber. With the exception of the use of this large chamber, standard Peet-Grady procedure was followed. The Official Test Insecticide was used. The results were:

	Per Cent Kill, 24 Hours	10 Minute Knock-down
0.05% Pyrethrins:		
Base Oil C	23	96
Preferred Solvent	11	93
0.1% Pyrethrins:		
Base Oil C	25	99
Preferred Solvent	38	99
0.2% Pyrethrins:		
Base Oil C	46	99
Preferred Solvent	78	100
Official Test Insecticide	38	98
0.12% Pyrethrins in Preferred Solvent	50	-----
0.31% Pyrethrins in Base Oil C	50	-----

Example III

Solutions of "DDT," 2,2-bis(paradichlorophenyl)-1,1,1-trichloroethane, were similarly prepared and tested. The results were:

	Per Cent Kill, 24 Hours	10 Minute Knock-down
0.05% DDT:		
Base Oil C	54	100
Preferred Solvent	88	100
0.1% DDT:		
Base Oil C	84	100
Preferred Solvent	96	100
0.2% DDT:		
Base Oil C	98	100
Preferred Solvent	99	100
0.11% DDT in Base Oil C	88	-----
Official Test Insecticide	33	100

Example IV

75 Solutions of commercial grade chlorinated

naphthalene were similarly prepared and tested. The results were:

	Per Cent Kill, 24 Hours	10 Minute Knock-down
0.025% Chlorinated Naphthalene:		
Base Oil C.....	29	100
Preferred Solvent.....	39	100
0.05% Chlorinated Naphthalene:		
Base Oil C.....	65	100
Preferred Solvent.....	80	100
0.1% Chlorinated Naphthalene:		
Base Oil C.....	89	100
Preferred Solvent.....	97	100
Official Test Insecticide.....	31	100
0.05% Chlorinated Naphthalene in Preferred Solvent.....	90	

Example V

Solutions of commercial grade butyl carbitol thiocyanate were similarly prepared and tested. The results were:

	Per Cent Kill, 24 Hours	10 Minute Knock-down
1.0% Butyl Carbitol Thiocyanate:		
Base Oil C.....	5	99
Preferred Solvent.....	4	91
3.5% Butyl Carbitol Thiocyanate:		
Base Oil C.....	22	100
Preferred Solvent.....	53	100
7.0% Butyl Carbitol Thiocyanate:		
Base Oil C.....	63	100
Preferred Solvent.....	94	100
7.2% Butyl Carbitol Thiocyanate in Base Oil C.....	60	
Official Test Insecticide.....	49	99

A very large number of other tests were made using the above toxic materials in combination. Definite synergistic action of the preferred solvent was shown by the results. Solvents having various boiling ranges in the range from 300° F. to 480° F. were tested and were found effective in connection with the above mentioned toxic materials and with rotenone. As an example of the relatively efficiency of branched chain paraffin fractions boiling in this range we submit the following.

Example VI

0.1% solutions of pyrethrins in fractions were prepared. These were tested by Peet-Grady procedure and the following results, stated in percentage of kill in 24 hours above that shown by the Official Test Insecticide, were obtained:

Fraction boiling from 300° F. to 360° F. 30.6
 Fraction boiling from 360° F. to 410° F. 39.5
 Fraction boiling from 400° F. to 480° F. 15.6

Fractions boiling above 480° F. were found to have greatly reduced killing power.

We do not know the mechanism by which increased insecticidal power results from the use of our solvents with commonly used toxic materials in insecticides. Apparently it results from the high percentages of secondary and/or tertiary carbon atoms present in such solvents, but we do not wish to be limited to any theory of chemical or physiological action. The synergistic action of such solvents with pyrethrins, rotenone, "DDT," "DDD," benzene hexachloride, butyl carbitol thiocyanate, etc., is such that effective insecticides may be prepared using much smaller quantities of toxic material when these solvents are used. Low odor of product may be obtained making masking materials unnecessary, but these may be used if desired without decreasing the

effect of the solvent. The solvents described are relatively non-toxic to human beings and do not noticeably irritate the eyes, nose or skin.

We claim:

5. 1. An insecticide consisting essentially of a mixture of branched chain paraffin hydrocarbons having the following characteristics:

	Properties	Test Results	Test Method
Distillation (760 mm.)			ASTM D86-45.
IBP ² F.	368		
10%	372		
20%	373		
50%	375		
70%	377		
90%	384		
95%	389		
E.P.	403		
Specific Gravity, at 60/60° F.	0.7649		ASTM D287-39.
Refractive Index, at 20° C.	1.4242		ASTM E8-45a.
Flash Point (TCC), ° F.	143		ASTM D56-36.
Bromine Number	1.2		ASTM E8-45a.
Residual Odor Test	None		ASTM D288-44.
Odor	1 Neutral		

¹ No naphtha or kerosene odor.

25 2. The insecticide of claim 1 in which said insect poison is soluble in said mixture of branched chain paraffins, characterized by the property of having a higher insecticidal power than an insecticide of the same concentration of said insect poison dissolved in a kerosene.

30 3. The insecticide of claim 1 in which said insect poison is 2,2-bis(parachlorophenyl)-1,1,1-trichloroethane present in an amount equal to from 0.05 to 0.2 per cent.

35 4. The insecticide of claim 1 in which said insect poison is pyrethrins present in an amount equal to from 0.1 to 0.2 per cent.

40 5. The insecticide of claim 1 in which said insect poison is butyl carbitol thiocyanate present in an amount equal to from 1 to 7 per cent.

50 5. An insecticide consisting essentially of a mixture of branched chain paraffin hydrocarbons containing secondary and tertiary carbon atoms and produced by synthesis from lower-boiling aliphatic hydrocarbons, and boiling in the range from 360° F. to 410° F., and dissolved therein 0.025 to 7 per cent of an insect poison soluble in said mixture of branched-chain paraffins, characterized by the property of having a higher insecticidal power than an insecticide of the same concentration of said insect poison dissolved in a kerosene.

55 6. An improved insecticide comprising at least 93 per cent by weight of a mixture of branched chain paraffin hydrocarbons boiling in the range from 360° F. to 410° F., said mixture having the property of increasing the insecticidal power of an insect poison dissolved therein as contrasted with the lack of such a property in a kerosene insecticide solvent; and at least 0.025 per cent by weight of at least one insect poison soluble in said mixture of branched chain paraffin hydrocarbons.

65 7. The insecticide of claim 6, wherein said insect poison is "DDT," 2,2-bis(paradichlorophenyl)-1,1,1-trichloroethane, which is present in an amount of at least 0.05 per cent by weight.

70 8. The insecticide of claim 6, wherein said insect poison is pyrethrin which is present in an amount of at least 0.1 per cent by weight.

9. The insecticide of claim 6, wherein said insect poison is chlorinated naphthalene.

75 10. The insecticide of claim 6, wherein said insect poison is butyl carbitol thiocyanate which

is present in an amount of at least 3.5 per cent by weight.

11. The insecticide of claim 6, wherein said insect poison is rotenone.

12. An improved insecticide consisting essentially of a mixture of branched chain paraffin hydrocarbons boiling in the range from 360° F. to 410° F., said mixture having the property of increasing the insecticidal power of an insect poison dissolved therein as contrasted with the lack of such a property in a kerosene insecticide solvent; and at least one insect poison soluble in said mixture of branched chain paraffin hydrocarbons.
